LOGGING RIG

Carl Torner, Olympia, Wash.

Application November 15, 1937, Serial No. 174,703

1 Claim. (Cl. 212—92)

My invention relates to block and tackle rigs for logging operations and more particularly to carriage locking and releasing devices for the fall block carriages of such rigs.

As explanatory, in hauling logs uphill it is the practice to use a rig including a carriage mounted on an overhead cable line, called the sky line, running from a fixed point uphill to a vertical spar, tree, or the like, the carriage being pulled by a cable, called the main line, attached thereto and reeled up on a winch, and the logs suspended, or hooked, in a loop of the cable by means of a pulley, called a fall block. As will be understood the log is dropped, or let loose, at any desired point by slackening up on the main line to lower the fall block.

The object of my invention is to equip a rig of this character with efficient means for locking the carriage to the sky line against retrograde movement in any selected position along said line so that logs may be dropped at any point along the line as desired.

Another object is to provide means for the purpose above set forth adapted to unlock the carriage from the sky line by pull exerted on the main line.

To the accomplishment of the above, and subordinate objects presently appearing, a preferred embodiment of my invention has been illustrated in the accompanying drawings, set forth in detail in the following description, and defined in the claim appended hereto.

In said drawings:

Figure 1 is a fragmentary view in side elevation illustrating a rig of the character indicated equipped according to my invention.

Figure 2 is a similar view drawn to an enlarged scale and with parts shown in section illustrating the operation of the invention.

Figure 3 is a fragmentary view in horizontal section taken on the line 3—3 of Figure 4 looking downwardly.

Figure 4 is a view in vertical transverse section taken through the carriage on the line 4—4 of Figure 2 looking in the direction indicated by the arrows.

Figure 5 is a view in transverse section taken on the line 5—5 of Figure 2 and illustrating details of the bumper.

Figure 6 is a view in perspective of a guide block forming part of the bumper, and

Figure 7 is a view in perspective of a locking dog.

Referring to the drawings by numerals, my invention has been illustrated therein as incor-

porated in a rig in which 1 designates the usual vertical spar, pole, or tree, supporting the overhead line, or sky line, 2 to incline upwardly thereto by means of the usual jack 3 secured to said spar, as at 4, the line 2 having its opposite ends 5 suitably fixed adjacent to the ground in a manner immaterial to a proper understanding of the invention and therefore not illustrated in the drawings. The carriage 5 comprises a pair of side plates 6 straddling the sky line 2 and suspended 10 therefrom by means of a pair of sheaves 7 rotating between said plates 6 on arbors 8 having their ends suitably mounted in said plates. Rods 9 and spacing sleeves 10 secure the plates 6 together. The main line 11 is connected at one 15 end, as at 12, to the carriage 5 below the sky line 2, as by stud 13, and trained over the bull block 14 which is affixed to the spar 1, adjacent the jack 3, by a ring 15 surrounding said spar and a swivel 16 on said block looping around the ring. The 20 other end of the main line 11 is attached to a winch or hoist not shown. The fall block 17 runs in a slack, or loop, between carriage 5 and the bull block 14 and carries a cable 18 for the attachment of the logs thereto.

In the operation of the described type of rig the logs are hauled up towards the spar 1 to be dropped at any predetermined point by slackening up on the main line and thereby lowering the fall block 17 and logs.

According to my invention, a bumper 19 is slidably mounted on the sky line 2 between the carriage 5 and spar 1 and comprising a cylindrical block 21 of hard wood having an axial bore 20 through which the sky line 2 extends and which 35 is of a proper size to frictionally grip said line. The described block 21 is enclosed by a substantially cylindrical sheath co-extensive in length with the block 21 and comprising a pair of complementary semi-cylindrical sections 23 and 24 40 hinged together as at 25 along the bottom of the block 21 and having opposed flanges 26 extending along the top of the block 21 bolted together as at 27 whereby the sections 23 and 24 are clamped around said block 21. The flanges 26 are provided with ears 27 apertured, as at 28, for the passage of a cable 29 therethrough by means of which the bumper is secured to the spar 1 against movement away from the latter. The ends of the sections 23 and 24, at the carriage end of the 50 bumper, are out-turned laterally to provide a flange 30 extending around the sheath 19. Pivotally mounted intermediate its ends between the plate 6, as at 31, is a locking dog 32 vertically swingable on its pivot 31 to engage a hooked end 55

33 thereon with the flange 30 and having a cam edge 34 for cooperation with said flange to cam said hooked end downwardly. The hooked end 33 is normally urged upwardly towards the flange 5 39 by means of a bifurcated counter-balance weight 35 straddling the lower edges of the carriage plates 6 and swingably mounted on the aforementioned stud 13. The weight 35 is operatively connected to the end of the dog 32, opposite 10 the hooked end 33, and by means of a link 36 pivoted to said weight, as at 37, and to said end of the dog 32 as at 38. One of the before-mentioned spacing sleeves 10 limits upward movement of the hooked end 33 of the dog 32.

15 Referring to the operation of the invention, the bumper 19 is located along the sky line 2 in any position in which it is desired to drop the log, or logs, and secured in location against movement away from the spar by means of the cable 20 29. As the carriage 5 reaches the approximate desired position the hooked end 33 of the locking dog 32 is cammed downwardly by the cam edge 34 engaging with the flange 30 and against the action of the counter-balance weight 35 to 25 snap under and behind said flange under the influence of said weight upon further movement of the carriage towards said position. As the carriage 5 proceeds further it engages the bumper 19 and is retarded thereby so that the operator 30 is thus advised that the proper position to unload has been reached. The main line 11 may now be slackened to lower the fall block 17 and log. As will be obvious retrograde movement of the carriage 5 is prevented past the selected position 35 by the described locking coaction of the locking dog 32 and flange 30. The weight 35 is so arranged that by pulling up on the main line 11

to take up all slack therein said main line may be engaged with said weight to rock the latter in the proper direction to effect downward movement of the hooked end 33 of the dog 32 away from the flange 30 and thereby unlock the carriage 5 from the bumper 19 as will be clear. 5

My invention will, it is believed, be clearly understood from the foregoing without further explanation.

Manifestly the invention as described is susceptible of modification without departing from the inventive concept and right is herein reserved to all such modifications falling within the scope of the subjoined claim. 10

What I claim is:—

In a rig of the class described, the combination with an overhead inclined cable, an upright supporting the cable at the high end thereof, and a carriage traveling on the cable, of means for locking the carriage to the upright against retrograde movement including a bumper member on the cable at the high end thereof and anchored to the upright, a pivoted locking dog on said carriage vertically movable into and from interlocking relation with said bumper, a weight pivoted 20 on the carriage and operatively connected to the dog for gravitational movement to overbalance said dog toward interlocking relation, said weight being swingable against the influence of gravity to move the dog from interlocking relation, and a pull line connected to the carriage to propel the same toward the high end of the cable and engageable with the weight under the pull exerted thereagainst to swing the latter against the influence of gravity. 25 30 35

CARL TORNER.
